SIGNAL FOR AUTOMATIC VEHICLE
OVERDRIVE

Walter Pilgram, Jr., Long Mott, Tex.

Application January 12, 1951, Serial No. 205,631

3 Claims. (Cl. 340—52)

1

This invention relates to signals for automotive vehicle overdrives and more particularly to a signal adapted to be mounted in a vehicle for observation by the vehicle driver to indicate an operating condition of a vehicle equipped with automatic overdrive in which the overdrive is not in operation and the speed of the vehicle is such that the overdrive would function if put into operation.

It is among the objects of the invention to provide a signal system for an automotive vehicle equipped with automatic overdrive which provides a signal device, such as a signal lamp, mounted on the vehicle for observation by the vehicle driver and means connecting the signal device to the overdrive mechanism, so that the signal device will be energized when the overdrive mechanism is held out of operation and the speed of the vehicle and other conditions are such that the overdrive would function if put into operation, to warn the driver that the overdrive is not in use at a time when it could be in use to increase the operating efficiency of the vehicle and in which the signal device is de-energized at all other times; which can be mounted on the vehicle and connected to the overdrive mechanism with no material modification of the vehicle or the overdrive construction; which can be provided as a kit for merchandising and can be installed on an existing vehicle equipped with automatic overdrive; which does not interfere in any way with the normal operation of the overdrive mechanism and utilizes current from the vehicle electrical system only when the current generator of the electrical system is in operation; and which is simple and durable in construction, economical to manufacture and easy to install, and reliable in operation.

Other objects and advantages will become apparent from a consideration of the following description and the appended claims in conjunction with the accompanying drawing wherein the single figure is a diagrammatic illustration of an automatic vehicle overdrive mechanism with a signal device illustrative of the invention operationally connected thereto.

With continued reference to the drawing, the overdrive mechanism is illustrated with various associated parts of the vehicle on which it is installed, such parts including the vehicle ignition coil 10 having two primary terminals 11 and 12 and a secondary terminal 13, a vehicle ignition distributor 14 having a primary terminal 15 connected to the primary terminal 11 of the coil by a conductor 16 and a secondary or high tension terminal 17 connected to the secondary terminal 13 of the coil by a conductor 18. The vehicle

2

parts further include an ignition switch 19 having three terminals 20, 21 and 22 of which the terminal 22 is connected to the primary terminal 12 of the ignition coil 10 by a conductor 23. The terminal 20 of the ignition switch is connected by a conductor 24 to one terminal of a fuel gauge and ammeter combination 25, and the other terminal of the combination 25 is connected through a conductor 26 to the terminal 21 of the ignition switch. An engine starter relay switch 27 has one main terminal 28 connected through a conductor 29 with the vehicle battery 30 and a conductor 31 leads from the starter relay switch terminal 28 to the ammeter and gasoline gauge combination 25, so that when the ignition switch 19 is closed current will flow from the battery through the conductor 29 to the starter relay switch terminal 28, from this terminal 28 through the conductor 31 to one side of the ammeter, from the other side of the ammeter through the conductor 26 to the ignition switch and from the ignition switch through the conductor 23 to one side of the ignition coil 10. From the ignition coil 10 the current flows through the conductor 16 to the terminal 15, one side of which is connected to the make and break points of the distributor 14, the other side of these make and break points being grounded, as indicated at 32. The high voltage current generated by the coil 10 is conducted from the coil to the distributor through the conductor 18 and from the distributor to the engine spark plugs which are grounded, as is well known to the art.

The vehicle change speed transmission is indicated at 33 and has the usual selectively engageable gears shiftable by the shift arms 34 and 35 by a hand operated lever, not illustrated, mounted at a location convenient to the vehicle driver, and the numeral 36 indicates the front universal joint of the vehicle drive which is connected to the front end of the vehicle drive shaft as is well known to the art.

The overdrive mechanism, generally indicated at 38, is disposed between the rear end of the vehicle transmission 33 and the front universal joint 36 for increasing the speed of the universal joint 36 and the drive shaft relative to the speed of the output shaft of the change speed transmission 33. This overdrive mechanism includes a housing 39 mounted at its front end on the rear end of the change speed transmission by suitable means, such as the bolts 40 extending through apertured flanges on the transmission housing and the overdrive housing 39 and the output shaft 41 of the change speed transmission is extended into the overdrive housing 39. An overdrive output shaft 42 extends through the rear-

ward portion of the overdrive housing from a location adjacent the rear end of the shaft 41 to the front universal joint 36 to which it is drivingly connected by means well known to the art.

A one-way drive clutch 43 is connected between the shaft 41 near the rear end of the latter and the shaft 42 at the front end of this shaft to provide a direct drive in one direction through the overdrive mechanism and to permit the vehicle to free-wheel relative to the engine at speeds below the cut-in speed of the over-drive mechanism.

A planetary gear train, generally indicated at 45, is also connected between the shafts 41 and 42 in series with the one-way clutch 43 and includes an outer ring gear 46 drivingly connected to the shaft 42 through the outer housing or race of the one-way clutch 43, an inner sun gear 47 slidably and rotatably mounted on the shaft 41, a planetary gear cage 48 connected to the transmission output shaft 41, and planetary gears 49 carried by the cage 48 and meshing with the ring gear 46 and sun gear 47.

A disc 50 is slidably, but non-rotatably connected to the sun gear 47 and is provided with one or more peripheral notches and a locking dog 51 is slidably mounted in the housing 39 for movement toward and away from the disc 50. When this locking dog is engaged in a notch in the disc, it holds the disc and the sun gear 47 against rotation and under these conditions the drive is from the shaft 41 through the planetary cage 48 to the planet gears and these gears, rotating around the fixed sun gear 47, drive the ring gear 46 at a speed higher than the rotational speed of the transmission output shaft 41, the overdrive mechanism being then in operation.

A collar 52 is mounted on the sun gear and has a peripheral groove into which a fork 53 projects for sliding the sun gear longitudinally of the shaft 41. When the sun gear is moved in one direction a set of teeth on the sun gear are brought into engagement with a set of teeth provided in the front end 54 of the planetary gear cage to lock this cage against rotation relative to the sun gear. This locks up the entire planetary gear unit and provides a direct drive through the overdrive mechanism with no over-drive or speed increasing function and no overrunning.

The locking dog 51 is operated by a solenoid, generally indicated at 55, having an armature 56 connected to the dog 51, an operating coil 57 and a holding coil 58. When the operating coil 57 of the solenoid is energized, it moves the locking dog 51 into engagement in the notch of the disc 50 and, as this coil is grounded at one side through a switch 59 which is opened by the armature 56 when the dog 51 is engaged in the notch in the disc 50, this actuating coil 57 is de-energized as soon as the locking dog has been moved into engagement in the notch in the disc. This leaves the holding coil 58 energized, since this coil is independently grounded, as indicated at 60, to hold the locking dog in engagement with the disc.

A balk ring 44 is rotatably mounted on drive shaft 41 at one side of the gear plate 50 and is in frictional engagement with one side of the gear plate. When the vehicle carrying the over-drive mechanism is operating at a speed below that at which the overdrive can go into operation, the balk ring is turned into engagement with the locking dog or pawl 51 and is effective to hold the pawl out of engagement with the gear

plate 50. When the speed of the vehicle reaches that at which the overdrive mechanism should become operative, the balk ring still holds the detent out of engagement with the gear plate 50 to avoid damage to the mechanism by suddenly stopping the gear plate while power is being transmitted through the overdrive mechanism. In order for the pawl to engage the gear plate and put the overdrive mechanism into operation, it is necessary for the vehicle operator to permit the engine throttle to partly close for a brief interval, thereby momentarily reducing the transmitted power until the shaft 42 starts to overrun the shaft 41. The ring gear 46 now overrunning the sun gear 47 rotates the pinions 49 because of the connection of pinion cage 48 to the slower moving shaft 41 and rotates sun gear 47 and gear plate 50 in a reverse direction until balk ring 44 is moved out of engagement with pawl 51 and the pawl is then moved by solenoid 55 into engagement with gear plate 50. Upon resumption of power, the vehicle will now be in overdrive.

Simultaneously with the opening of the switch 59 the movement of the solenoid armature 56 causes a ground switch 61 to close for a purpose which will presently appear.

A governor, generally indicated at 62, is mounted on the housing 39 and the output shaft 42 of the overdrive mechanism is drivingly connected to this governor. The governor includes an electric switch 63, one side of which is grounded, as indicated at 64.

A lock-out shifter rail 65 extends longitudinally of the housing 39 substantially parallel to the shafts 41 and 42 which are coaxial with each other, and is slidably mounted in the housing. A cam shaft 66 is rotatably mounted in the housing 39 substantially perpendicular to the rail 65 and has at one end a cam which engages in a notch in the rail 65 to move the rail 65 longitudinally upon rotation of the shaft 66. An actuating lever 67 is mounted on the cam shaft 66 at the outer end of the latter and is connected to a suitable handle located convenient to the driver, so that the driver can lock the overdrive mechanism out of operation, if he so desires. The shaft 66 carries an enlargement 68 which engages in a recess in the dog 51 when the rail 65 is moved to its lock-out position and holds the dog against engagement in the notch of the disc 50. The fork 53 is also mounted on the rail 65 and is effective to move the sun gear to lock up the planetary gear unit of the overdrive mechanism, as explained above, when the rail 65 is moved to its lock-up position.

A switch 69 is mounted on the housing 39 at one end of the rail 65 and is closed when the rail 65 is in position for operation of the overdrive mechanism and is opened when the shaft 65 is in its position locking the overdrive mechanism out of operation.

In addition to the manually operated arm 67 for locking the overdrive including the free-wheeling clutch 43 out of operation, there is a connection in the vehicle transmission 33 between the reverse drive connecting mechanism and the rail 65 which locks the overdrive mechanism out of operation whenever the vehicle transmission is placed in reverse gear.

A main overdrive control relay, generally indicated at 70, is provided and includes a normally open switch 71 and an electromagnet 72 which closes the switch 71 when the electromagnet is energized. This relay switch has four ter-

minals, as indicated at 73, 74, 75 and 76, of which the terminal 73 is connected to one side of the normally open switch 71 and the terminal 75 is connected to the other side of this switch. The terminal 73 is connected through a conductor 77 with the battery connected terminal 28 of the starter relay switch 27 and the terminal 75 is connected through a conductor 78 with the battery terminal of the solenoid 55, so that, when the normally open switch 71 is closed the solenoid will be energized for putting the overdrive into operation. The switch 71 is not closed, however, unless the electromagnet 72 is energized.

The terminal 76 is connected to one side of the electromagnet 72 and this terminal is connected through a conductor 79 with the battery lead 31 at the ammeter 25, so that electrical energy from the battery 30 is available at all times at the terminal 76. The terminal 74 is connected to the other side of the relay magnet 72 and this terminal is connected through a conductor 79' to one side of a normally closed "kick-down" switch 80 and the other side of switch 80 is connected by a conductor 81 with one side of the lock-out actuated switch 69. The other side of the switch 69 is connected through a conductor 82 with the ungrounded side of the governor actuated switch 63. With this arrangement, if the lock-out mechanism is in released condition, so that the switch 69 is closed, and the overdrive mechanism is conditioned to function, if the governor closes the switch 63, a ground contact will be established from the terminal 74 on the main overdrive relay 70 through the conductor 79, the "kick-down" switch 80, the conductor 81, the lock-out actuated switch 69 and the governor actuated switch 63, and the electromagnet 72 will then be energized to close the switch 71 and energize the solenoid 55 to place the overdrive mechanism in operation as soon as the vehicle operator interrupts the power to free the dog 51 from the balk ring 44.

If the overdrive mechanism is locked out by manual movement of the lock out arm 67 and lock out rail 65, the switch 69 will be opened and it will not be then possible to establish an energizing circuit for the electromagnet 72 to close the switch 71 and the solenoid 55 cannot then be energized to stop the disc 50.

When the solenoid is in operating condition, it may become necessary to temporarily discontinue the overdrive in order to accelerate the vehicle rapidly, even though it is already traveling at a speed at which the overdrive is rendered effective. The "kick-down" switch 80 is provided for this purpose and has four terminals 84, 85, 86 and 87 of which the terminals 84 and 85 are connected to the conductors 79' and 81 respectively, and are normally connected by the switch 80. The terminal 86 is connected by a conductor 88 to the distributor terminal 15 and the terminal 87 is connected by a conductor 89 to the terminal of the ground switch 61 actuated by the armature of the solenoid 55. The "kick-down" switch 80 is disposed directly below the accelerator pedal of the vehicle or connected to the vehicle throttle in a manner such that when the throttle is fully opened, this switch will be operated to disconnect the terminals 84 and 85 and connect the terminals 86 and 87. When the terminals 84 and 85 are disconnected the electromagnet 72 of the main overdrive relay 70 is de-energized, permitting the switch 71 to open and this de-energizes the solenoid 55. The solenoid has a compression spring acting against the solenoid coils 57 and

58 to move the dog 51 out of engagement with the disc 50 when the solenoid coils are de-energized. However, with power being transmitted through the overdrive, the dog cannot be released from the disc unless the power is temporarily discontinued. As soon as the "kick-down" switch interconnects the terminals 86 and 87 the ignition distributor terminal 15 is grounded, interrupting the ignition of the vehicle engine, this grounding taking place through the ground switch 61 in the solenoid 55. This interruption of the engine power releases the dog 51 from the plate 50 and the solenoid spring immediately moves the solenoid armature to a position to remove the dog 51 from the plate 50 and open the ground switch 61, whereupon the overdrive is put out of operation, driving through the one-way clutch 43 instead of through the planetary gear assembly, and the ground switch 61 is opened, so that the operation of the vehicle engine is resumed. Operation of the overdrive will not be resumed until the engine throttle is closed sufficiently to permit the "kick-down" switch 80 to reconnect the terminals 84 and 85, and the vehicle to overrun the engine sufficiently to move the balk ring 44 out of engagement with the pawl 51.

As the construction and operation of automatic overdrives for automotive vehicles are well known to the art, and as overdrive and its electric system constitutes no part of the present invention except in the combination thereof with the novel signal means, the diagrammatic illustration on the accompanying drawing and the above brief description is considered sufficient for the purposes of the present disclosure.

With the above described arrangement, it may happen that the vehicle operator fails to interrupt the engine power sufficiently to release the pawl from the balk ring and permit the overdrive to go into operation under driving conditions at which it could be used to advantage. The present invention provides a signal, preferably in the form of a lamp, which is clearly visible to the driver, which advises the driver when the overdrive mechanism is precluded from operation under driving conditions where it could be used to advantage.

In accordance with the present invention, a signal lamp 90 is mounted on some convenient support in the vehicle, as on the vehicle instrument panel, and is provided with two terminals 91 and 92, the terminal 92 being a ground connection, as indicated at 100. A relay switch, generally indicated at 93 is also provided and mounted in some convenient location on the vehicle. This signal relay includes a normally closed switch 94 and an electromagnet 95 which is effective to open the normally closed switch 94 when the electromagnet is energized.

A conductor 96 connects one side of the switch 94 to one side of the coil of the electromagnet 95, and a conductor 98 connects conductor 96 with the solenoid terminal 75 of the overdrive relay 50. The other side of the switch 94 is connected through a conductor 97 with the lamp terminal 91 and the other side of the coil of the electromagnet 95 is connected through a conductor 99 with the terminal of the ground switch 61 of the solenoid 55.

With this arrangement, if the governor switch has been closed incident to a vehicle speed sufficient for the overdrive to cut in, and the main overdrive relay switch has been closed and the solenoid energized, but the overdrive is held out

of operation by engagement of the balk ring with the gear plate locking pawl, current at the solenoid terminal of the main relay will flow through conductor 98, signal relay switch 94, conductor 97 and lamp 90 to ground connection 100 illuminating the lamp. As ground switch 61 is now held open by solenoid 55, signal relay magnet 95 will not be energized and switch 94 will be closed. When the operator interrupts the power to put the overdrive into operation, ground switch 61 10 closes and energizes relay signal magnet 95, opening relay switch 94 and extinguishing the signal lamp.

If the vehicle has been operating in overdrive and has been slowed down and subsequently brought up to overdrive speed, if the slowing down was sufficient to discontinue the overdrive, when speed is resumed the signal lamp will be illuminated indicating to the operator that the vehicle is not operating in overdrive, although driving conditions are suitable and that it is necessary to interrupt the power to return to overdrive.

After the "kick-down" switch has been operated to discontinue the overdrive operation and operation at less than full power, but at a speed for overdrive operation is resumed, if the power has not been sufficiently reduced to permit the overdrive to cut in, the signal lamp will be illuminated and the operator accordingly advised that to resume overdrive he must temporarily interrupt the power.

The signal assembly of the present invention may be provided in kit form including the signal lamp 90, the relay switch 93, and the conductors 96, 97, 98 and 99, of which the conductors 96 and 98 may be combined, if desired, and this signal assembly can be mounted on the vehicle and connected into the electric system of the overdrive to operate in the manner described above, with a minimum amount of work, and without any necessary modification of the construction of the vehicle or the overdrive mechanism or its electric system.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

I claim:

1. In combination with a vehicle automatic overdrive mechanism including an overdrive relay connected to the vehicle electric system and having a solenoid terminal, an overdrive controlling solenoid connected to said solenoid terminal and having a grounding switch which is closed only when the overdrive mechanism is in operation, and means rendering said solenoid ineffective to place said overdrive mechanism in operation except during an interruption of power transmitted therethrough, signal means for indicating a vehicle operating condition in which the vehicle speed is sufficient for use of the overdrive mechanism but the overdrive mechanism is held out of operation comprising a signal device adapted to be mounted on and grounded at one side to the vehicle for observation by the vehicle driver, a signal relay switch including a normally closed switch and an electromagnet which holds said

normally closed switch open when said electromagnet is energized, a first conductor connecting the other side of said signal device to one side of said normally closed switch, a second conductor 5 connecting the other side of said normally closed switch and one side of said electromagnet to the solenoid terminal of said overdrive relay switch to energize said signal device when said solenoid terminal is energized, and a third conductor connecting the other side of said signal relay electromagnet to the ungrounded side of said solenoid grounding switch to thereby energize said electromagnet and open said normally closed switch to de-energize said signal device when said solenoid functions to place the overdrive mechanism in operation.

2. In combination with a vehicle electric system grounded at one side, an overdrive electric system grounded at one side and including a solenoid for placing the overdrive in operation, an overdrive relay connected to said vehicle electric system and having a solenoid terminal connected to said solenoid, and a grounding switch operated by said solenoid and closed when said solenoid operates to place the overdrive in operation, and means precluding operation of said solenoid except when the power transmitted through the overdrive is reduced, signal means comprising a signal device grounded at one side, 20 a signal relay including a normally closed switch and an electromagnet effective to open said normally closed switch when energized, a conductor connecting the other side of said signal device to one side of the signal relay switch, conductor 25 means connecting the other side of said signal relay switch and one side of said signal relay electromagnet to the solenoid terminal of said overdrive relay for energizing said signal device whenever said solenoid terminal is energized, and a conductor connecting the other side of said signal relay electromagnet to said grounding switch to energize said electromagnet and de-energize said signal device by opening said normally closed signal relay switch when 30 said grounding switch is closed incident to operation of the overdrive.

3. In combination with a vehicle electric system and an overdrive relay system energized by said vehicle electric system only when the speed of the associated vehicle is suitable for overdrive, a signal electric system including a signal device grounded at one side, first means connecting the other side of said signal device to said overdrive electric system for energizing said signal device when said overdrive electric system is energized, a relay switch in said first means closed when ungrounded and open when grounded, and second means grounded at one side and connected at its other side to said relay switch and effective to ground said relay switch and de-energize said signal device whenever said overdrive electric system is energized and completely operated to place the associated overdrive in operation.
